SALT AND PEPPER CANDELABRA

Arnold Starkenberg, New York, N. Y., assignor to Starke Design Inc., Brooklyn, N. Y., a corporation of New York

Application October 27, 1955, Serial No. 38,597

Term of patent 3½ years

(Cl. D48—2)

Fig. 1.

Fig. 2.

Fig. 3.

The dotted lines shown in the drawing are for illustrative purposes only.

I claim:

The ornamental design for a salt and pepper candelabra, substantially as shown and described.
